UNITED STATES PATENT OFFICE.

REGINALD A. FESSENDEN, OF BRANT ROCK, MASSACHUSETTS, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

WIRELESS SIGNALING.

1,101,915.

Specification of Letters Patent. Patented June 30, 1914.

Application filed March 8, 1909. Serial No. 481,974.

To all whom it may concern:

Be it known that I, REGINALD A. FESSENDEN, a citizen of the United States, residing at Brant Rock, in the State of Massachusetts, have invented certain new and useful Improvements in Wireless Signaling, of which the following is a specification.

My invention relates to methods of sending and receiving wireless signals and more particularly to sending and receiving antennæ.

In the accompanying drawings forming a part of this specification Figure 1 shows a plan view and Fig. 2 an elevation of apparatus for accomplishing this purpose.

The invention herein disclosed has for its object the more efficient generation and reception of wireless signals.

In Figs. 1 and 2, 3 and 4 are two portions of a large capacity formed preferably of a spider's web of wires, or galvanized iron tape and supported above and insulated from the ground in any convenient way for example as shown by insulating posts 15, 15, 15 and at a convenient but preferably low height above the ground, for example 20 feet. The two parts of the capacity may be connected so as to form one capacity by throwing the switch 11 so as to make contact with the terminal 16. 1 and 2 are portions of another capacity similarly formed supported and insulated and lying on either side of the capacity 3, 4. The two portions 1 and 2 may be united together so as to form one capacity by throwing the switch 9 so as to make contact with the terminal 15. It is not necessary that the outer capacity 1, 2 should entirely surround the inner capacity 3, 4, as good results can be obtained without this, and more especially as regards directive reception and transmission. The inner capacity 3, 4 is connected through the variable inductions 12 to a source of high frequency oscillations, such as the alternating current dynamo shown at 5, 6 being one of the collector brushes. The other terminal of the dynamo 5 is connected through the leads 8, 8, 8 having carefully proportioned inductances 21, 21, 21 to the outer capacity 3, 4. Good results may also be obtained by connecting the leads 8, 8, 8 to the grounds 20, 20, 20 by means of the switches 22, 22, 22. These grounds 20, 20, 20 may if desired and (also the capacity 1 and 2) be placed al-

most a complete quarter wave length away 55 from the capacity 3, 4 but in practice are generally placed closer. When the outer capacity 1, 2 is used it is preferably connected to ground by means of switches 10, 10, 10. The leads 8, 8, 8 are preferably 60 made to have as small capacity to ground as possible, and to have low resistance and no unnecessary self-induction. The inductance 21, 21, 21 are principally of use in controlling the flow of the oscillations from the 65 dynamo terminal to the outer capacity and capacity 24 may also be used in the leads and also employed to adjust the wave length. 25 is a telegraph key.

In the preferred method of operation the 70 dynamo 5 gives the capacities 1, 2 and 3, 4 rapidly alternating charges. Electrostatic lines are produced in hoop form as shown in 23, 23 and these electrostatic loops repel each other and travel outward in the form of 75 electromagnetic waves. The action during reception of the waves is similar, the electrostatic lines on arriving bridge the capacities and collapse through the receiver 27, the switch 26 being thrown for that purpose 80 so as to cut out the dynamo and connect the receiver. Where the capacity 1, 2 is omitted the outer portions of the electrostatic loops go direct to earth, but otherwise the action is similar.

A certain and large proportion of the electrostatic lines, instead of being projected up into the air as shown at 23, would normally be shunted direct to ground, and their energy wasted. This objectionable effect is 90 overcome in two ways. First by placing horizontal circles of thin sheet iron 13 between the capacity 3, 4 and ground. These circles of sheet iron by their self induction tend to choke back and prevent the electromagnetic lines from going from the capacity 3, 4 to ground and from ground up again to the capacity 1, 2. Such loops of thin sheet iron may also be placed at 2, and as shown in cross-section at 14 and 14', and for 100 a similar purpose, i. e. so as to choke back the electrostatic line from the capacity 1, 2 or from the ground 20. An alternative way which may also be used in conjunction with the above described way is to place a wave-chute 19 on the ground as shown, and to make this wave-chute of very low ohmic resistance so that that part of the charge

which is shunted from the capacity 3, 4 to the wave chute, and thence along the wave-chute and up to the capacity 1, 2 instead of being projected up into the air as shown at 5 23, should have a very low resistance path to travel, and hence may oscillate backward and forward without wasting any energy, and having a natural period as little pronounced as possible.

10 By means of this invention I am enabled to do away with high masts and expensive antennæ and to accomplish other useful purposes such as increasing the efficiency.

Having thus described my invention and 15 illustrated its use, what I claim as new and desire to secure by Letters Patent, is the following:

20 1. An antenna for wireless telegraphy comprising a large capacity, arranged approximately horizontally and elevated from the earth a very short distance and means comprising a plurality of low resistance conductors arranged in proximity to the earth and adjusted to dissipate any portion of the 25 electrical charge not utilized in producing radiation.

2. An antenna for wireless telegraphy comprising a large capacity arranged approximately horizontally close to the earth, 30 combined with means for reducing the idle charge thereon during radiation, comprising a series of low resistance conductors in proximity to the earth.

3. An antenna for wireless telegraphy comprising a conductor having large capacity and supported at a relatively low height above the ground; a second conductor similarly constructed and surrounding the first conductor the two conductors being connected to each other by leads having relatively small capacity to earth and containing means for adjusting the wave length, means for causing these said capacities to act as efficient radiators and absorbers of electromagnetic energy, said 40 means comprising circles of magnetic material placed between said capacities and ground and a low conducting path extending over the surface of the earth between the inner and the outer capacities. 50

4. An antenna for wireless signaling comprising in combination a conductor of large capacity in approximately horizontal position and close to the ground, and a second large capacity surrounding the first and in substantially the same plane, the two capacities being connected by leads containing means for adjusting the wave length, substantially as described.

In testimony whereof I have hereunder signed my name and in the presence of the two subscribed witnesses.

REGINALD A. FESSENDEN.
